UNITED STATES PATENT OFFICE.

CHARLES N. ECKLYN, OF RACINE, WISCONSIN, ASSIGNOR TO STANDARD ELECTRIC WORKS, OF RACINE, WISCONSIN, A CORPORATION OF WISCONSIN.

AGITATOR.

1,103,949.

Specification of Letters Patent. Patented July 21, 1914.

Application filed November 20, 1912. Serial No. 732,430.

To all whom it may concern:

Be it known that I, CHARLES N. ECKLYN, a citizen of the United States, residing at Racine, in the county of Racine and State 5 of Wisconsin, have invented certain new and useful Improvements in Agitators, of which the following is a specification.

My invention relates to agitators and has particular reference to a novel agitator or 10 mixer for beverages such as are served at soda fountains and similar places. It has been customary for some time to provide mechanically operated agitators for use in mixing certain beverages. Such agitators 15 as commonly constructed include a motor, usually electrically propelled, and a depending stem attached to the shaft of the motor, this stem carrying at its lower end a propeller. When liquids are to be treated by 20 this device the glass containing the liquid is raised in contact with the base, the stem carrying the propeller extending into the container. There are serious objections to 25 this type of agitator, the most important being that the stem after use is exposed to the air and accumulates dust. Furthermore, many of the beverages contain milk which remains on the stem and propeller after use. This becomes sour and rancid after a short 30 exposure to the normal heat of the room. In general, such devices are unsanitary and it is to overcome such difficulties that the present agitator has been devised.

Therefore, one of the principal objects of 35 the present invention as heretofore stated, is to provide a sanitary agitator. The container itself carrying the mixing propeller and being readily detachable from the motor stem, may be cleansed after each use there- 40 of. Another object is to provide in such a device a novel connection between the motor shaft and the propeller stem.

A still further object is to provide a novel 45 and effective gland by means of which leakage from the container may be prevented and one in which lubricant will not be required, such lubricant being unsanitary in view of the possibility of its contaminating the contents of the container.

The invention will be more readily understood by reference to the accompanying drawing, wherein,

Figure 1 is a side elevation, partly in sec-

tion, showing my novel agitator, and, Fig. 2 is a detail perspective of the connection between the motor shaft and propeller stem. 55

Referring more particularly to the drawings, it will be seen that I mount a motor 10, on a suitable base 11, having an electrical connection 12, controlled by a switch 13. 60 The motor shaft 14 extends vertically upward, terminating at a point just above a small shelf 15, of glass or other suitable material, this shelf resting upon a flange 16 of the upper shaft bearing 17. The shelf 15 is 65 securely held by means of a centering disk 18, having a concentric threaded opening which is adapted to be screwed on the threaded nipple of the motor bearing bracket 17.

The container 19 of my invention is pref- 70 erably constructed of glass and has a threaded lower end. The bottom is open to provide for the insertion of the propeller as desired. The base 20 has an upstanding screw-threaded flange 21, within which the 75 glass 19 is screwed. The base has a concentric threaded opening within which a housing 22 is seated, this housing having a peripheral flange 23, which limits its downward travel within the opening. The gland 80 or packing strip 24 is seated on the plane surface of the base member 20 and after the parts are assembled, the bottom of the glass and the flange 23 being securely thrust thereagainst, possible leakage of liquids in 85 the container is prevented. The housing 22 is perforated and accommodates a bushing 25, within which is seated a propeller shaft 26, carrying at its upper end a propeller 27.

A collar 28 is pinned to the shaft and a 90 further collar 29, also pinned to the shaft, provides a seat for a coiled spring 30, the other end of the spring being held by a hollow cap 31, adapted to fit over the end of the shaft 14. The shaft 14 is provided with 95 a pin 14^a, this pin registering with a cut-away portion 32, in the cap 31. If preferred, the cap may have only one or more depending lugs disposed in the path of the pin 14^a, when the cap is in place. This provides for the rotation of the cap and of the propeller 27, through the medium of the spring 30 and propeller shaft 26. The purpose of providing a helical spring is to assure the proper operation of the propeller 100 105 shaft 26 without binding even though the

container may not be accurately positioned above the motor shaft. The spring provides in effect a universal joint or wobbler.

In order to obviate the possibility of escape of liquids around the propeller shaft 26, I provide a gland or packing member 33, which is hollow or cup-shaped, having an opening for the passage of the shaft and provided with a flange 34, perforated to accommodate the adjusting screws 35. These screws are threaded and adapted to be seated in the housing 22. On the shanks of the screws are carried compression springs 36, these springs normally thrusting the gland 15 against the collar 28. Liquids such as milk, small quantities of which may escape around the shaft 26, will be prevented from further escaping and will in addition, provide a lubricant for the shaft. Thus no oil or grease 20 is necessary for the proper operation of the movable parts.

It will be seen from the above description that the glass and its base 20 may be readily lifted from off the motor unit, washed and 25 sterilized as desired, then connected to the motor by the simple act of placing the base upon the centering disk 18. The cap 31, because of this universal connection, will adapt itself to the shaft and by turning the switch 30 the agitating may proceed as desired. The object of screw-threading the lower end of the glass will be apparent. Assuming the glass is broken, it may be readily unscrewed and replaced by another without disturbing 35 in any way the mechanism carried by the base.

The mechanism described is extremely simple and will not readily get out of order. It may be changed or modified in many ways 40 and such modifications as are within the scope of the appended claims I consider to be within the spirit of my invention.

I claim:

1. In a device of the class described, the 45 combination of a liquid container having a removable bottom wall, an agitator carried by said removable wall, the shaft controlling said agitator projecting beneath said wall, a driving element having an upwardly projecting shaft, and means for disengageably uniting said shafts, substantially as described.

2. In a device of the class described, the 55 combination of a liquid container having a removable bottom wall, a propeller rotatably mounted in said bottom wall, a shaft connected to said propeller and projecting below said wall, a driving motor having an

upwardly projecting shaft, and means for flexibly interengaging said shafts, substantially as described. 60

3. A device of the class described, comprising in combination, a driving element having an upwardly projected driving shaft, a container, a propeller mounted within said container, driving means for said propeller, said driving means being projected through the bottom wall of said container, means for disengageably connecting said propeller shaft with the shaft of said driving element, and a universal joint interposed between said shafts, substantially as described. 70

4. A device of the class described, comprising in combination, a driving element having an upwardly projecting shaft, a container provided with a base, means for centering said base with relation to said driving element, a propeller within said container, a driving shaft for said propeller, said shaft being projected through the bottom of said container, and means for disengageably uniting the shaft of said driving element and said propeller shaft, substantially as described. 75

5. A device of the class described, comprising in combination, a container having an opening in its lower end, a base, means for detachably uniting said container and base, an agitator carried by said base, a shaft for said propeller, said shaft being projected 80 through the open lower end of said container, substantially as described. 85

6. A device of the class described, comprising in combination, a container having an open end, a base, means for detachably 95 uniting said container and base, a housing screwed in said base and projecting through the open end of said container, an agitator having a shaft carried by said housing, and a spring-operated gland acting to maintain 100 a fluid-tight connection between the interior of said housing and said shaft, substantially as described.

7. A device of the class described, comprising in combination, an open-ended screw- 105 threaded container, a base having screw threads and adapted to accommodate said container, and an agitator carried by said base and normally projected through the open end of said container, substantially as 110 described.

CHARLES N. ECKLYN.
